[57] CLAIM

The ornamental design for a casing for ventilator or the like, as shown and described.

DESCRIPTION

FIG. 1 is a front elevational view of a casing for ventilator or the like showing my new design;

FIG. 2 is a rear elevational view thereof;

FIG. 3 is an elevational view taken from one side thereof, the opposite side being a mirror image of the side shown;

FIG. 4 is a top plan view thereof;

FIG. 5 is a bottom plan view thereof; and

FIG. 6 is a perspective view taken from the top front and one side thereof.
